WELT-CHANNELING ATTACHMENT FOR SOLE-SEWING MACHINES.

1,017,380.

Specification of Letters Patent. Patented Feb. 13, 1912.

Application filed October 11, 1907. Serial No. 396,380.

To all whom it may concern:

Be it known that we, CARSON J. CADY and JOSEPH E. THAYER, citizens of the United States, residing, respectively, at 5 Rochester and West Bridgewater, in the counties of Monroe and Plymouth and States of New York and Massachusetts, have invented certain new and useful Improvements in Welt-Channeling Attachments for Sole-Sewing Machines; and we do hereby declare the following to be a full, clear, and exact description of the invention, such as will enable others skilled in the art to which it appertains to make and use 15 the same.

The present invention relates to welt channeling attachments for sole sewing machines and particularly to that class of welt channeling attachments which comprise a 20 knife movable into and out of operative position, mounted independently of the work table of the machine, and arranged to extend upwardly through the work support in position to cut a stitch-receiving groove or slit 25 in the upper surface of the welt in advance of the needle, so that the stitches, which secure the outsole and welt, can be sunk below the upper surface of the welt at the forepart of the shoe, and the subsequent operation of forming ornamental indentations 30 on the welt can be performed by an ordinary indenting wheel, without liability of injuring the stitches of the seam.

The objects of the present invention are 35 to provide a welt channeling attachment of the class above referred to, in which the channeling knife is so shaped as to be stronger and more rigid than knives which have heretofore been used, and in which 40 the channeling knife can be held firmly against the thrust of the work without engaging an abutment on the work support, so that the attachment can be used with the ordinary form of work support provided 45 with an awl and needle slot, and the necessity of cutting away the work support to form an abutment or of providing a special form of work support is avoided.

In one form of welt channeling attachment which has heretofore been devised, the welt channeling knife is formed upon the upper end of an arm composed of a flat piece of metal, being mounted below the work support upon a pivot, the lower end of

the arm extending in the direction of feed, 55 and the upper end of the arm extending through the awl and needle slot of the work support. To hold the welt channeling knife in position against the thrust of the work, it is necessary, with this form of 60 knife-carrying arm, to cut away a portion of the work support to form an abutment for the upper end of the arm.

In accordance with a feature of the present invention, a knife-carrying arm composed of a piece of flat metal is provided, 65 and this arm is twisted, a short distance above its lower end, through an angle of 90°, so that the metal in the upper portion of the arm is disposed in the best manner 70 to resist the thrust of the work, and this portion of the arm is rendered sufficiently stiff and rigid to maintain the welt channeling knife in position.

Another feature of the present invention 75 contemplates the provision, in a welt channeling attachment provided with a knife carrying arm supported independently of the work support, of a brace arranged to engage the arm above its pivot and support the arm against the thrust of the work. 80 This feature of the invention may be used with any suitable form of knife-carrying arm, but is particularly adapted for use with the knife-carrying arm above referred 85 to as constituting a feature of the present invention, since the upper portion of this arm is of sufficient rigidity to withstand the thrust of the work, and by the provision of a brace engaging the arm above its pivot, 90 the lower portion of the arm is supported, and the arm can be used without the necessity of providing any abutment on the work support for the upper end of the arm. In its broader aspects this feature of the present 95 invention contemplates the use of any suitable form of brace. In the preferred form of the invention, however, the brace is pivotally mounted concentrically with the knife carrying arm and is adapted to swing with 100 the arm.

In addition to the features above referred to the present invention also consists in certain constructions and arrangements of parts hereinafter described and claimed the advantages of which will be obvious to those skilled in the art from the following description. 105

The present invention will be clearly understood from the accompanying drawing, in which—

Figure 1 is a view in front elevation of 5 the preferred form of the attachment together with so much of a sole sewing machine as is necessary to show the connection of the attachment therewith. Fig. 2 is a view in side elevation of the edge gage slide 10 of the sewing machine with the welt channeling knife mounted thereon, the knife arm being shown as extending upwardly through the awl and needle slot of the work support, which is shown in section, and the 15 parts being in the position which they assume when the channeling knife is in a position to cut a channel in the welt. Fig. 3 is a detail sectional view taken on the line 20 α — α of Fig. 2. Fig. 4 is a detail view of the adjustable eccentric sleeve upon which the knife carrying arm is mounted and by 25 which it is adjusted vertically, and Figs. 5 and 6 are detail views in rear and side elevation respectively of the knife carrying arm.

In the drawing 1 indicates the curved hook needle, 2 the work support or table, 3 the edge gage and 4 the edge gage slide of a sole sewing machine, such for instance as 30 is disclosed in the patent to French and Meyer, No. 473,870, dated April 26, 1892. The slide 4 is mounted to move transversely to the direction of feed upon a fixed guide 5, and is actuated at the desired times by the 35 operator from the feed changing lever 6, said lever being connected by a link to an arm 7, secured to the lower end of a rock shaft 8, mounted in a stationary block 9, which shaft is provided at its upper end 40 with a slotted arm 10 which engages a pin 11 projecting downwardly from the slide 4.

The construction, arrangement and mode 45 of operation of the edge gage slide and the mechanism by which it is operated are well known to those skilled in the art and need not be more specifically described herein.

The knife carrying arm of the illustrated embodiment of the present invention is indicated at 12 and is mounted, as usual in attachments of the class to which the present invention relates, upon an adjustable eccentric sleeve 13 which is clamped to one side of the edge gage slide 4 by means of a bolt 14. The upper end of the knife carrying 50 arm is provided with a welt slitting knife 15 of usual form and projects through the awl and needle slot of the work support 1 in position to cut a channel in the upper surface of the welt in advance of the needle. The 55 welt channeling knife 15 is moved into and out of operative position in the usual manner by moving the edge gage slide 4, the knife being projected when the edge gage slide is moved forward and being retracted 60 when the edge gage slide is moved to the 65

rear. To enable the knife to be projected and retracted in this manner it is necessary that the pivot for the lower end of the knife carrying arm extend in the direction of feed as will be obvious from an inspection of 70 Figs. 1 and 2. To enable the knife carrying arm to be so pivoted and at the same time to give the arm the greatest possible strength and rigidity, the arm is twisted through an angle of 90° a short distance above its lower 75 end, so that the greatest width of the upper end of the arm extends in the direction of feed. The twisting of the arm causes its upper end to be of sufficient rigidity to support the channeling knife against the thrust 80 of the work so that the upper end of the arm can extend loosely through the awl and needle slot of the work support and no supporting abutment for the upper end of the arm is required. To prevent the arm from 85 yielding at its lower end when the work is forced against the welt channeling knife, a brace 16 is provided, which brace consists of an arm pivotally mounted upon the bolt 14 outside of the sleeve 13 and having its upper 90 end arranged to engage the arm 12 above the point at which it is twisted. To cause the brace to swing with the knife carrying arm and to prevent its being accidentally disengaged therefrom, the upper end of the 95 brace is provided with lugs extending on each side of the arm.

From the description given above it will be seen that a welt channeling attachment constructed in accordance with the present 100 invention, in addition to being strong and durable and capable of use with the ordinary form of work support, can be of simple construction, and that the parts can be so arranged as to take up very little space and 105 not interfere with other working parts of the machine.

The nature and scope of the present invention having been indicated and the preferred form of the invention having been 110 specifically described, what is claimed is:—

1. A sole sewing machine, having, in combination with the stitch forming devices, a work support, an arm pivotally mounted below the work support upon an axis extending in the direction of feed and having its upper free end engaging the awl and needle slot of the work support, said arm consisting of a flat piece of metal having its lower 115 end portion arranged at right angles to the upper portion, a welt channeling knife upon the upper end of the arm, and a movable support for the lower end of the arm.

2. A sole sewing machine, having, in combination with the stitch forming devices, a work support, an arm pivotally mounted below the work support and having its upper free end engaging the awl and needle slot of the work support, a welt channeling knife upon the upper end of the arm, and a brace 125 130

engaging the arm above its pivot and acting to support the arm against the thrust of the work.

3. A sole sewing machine, having, in combination with the stitch forming devices, a work support, an arm pivotally mounted below the work support and having its upper free end engaging the awl and needle slot of the work support, said arm consisting of 5 a flat piece of metal twisted through an angle of 90° near its lower end, a welt channeling knife upon the upper end of the arm, and a brace engaging the arm above the point at which it is twisted.
- 10 4. A sole sewing machine, having, in combination with the stitch forming devices, a work support, an arm pivotally mounted below the work support and having its upper free end engaging the awl and needle slot 20 of the work support, a welt channeling knife upon the upper end of the arm, and a brace pivotally mounted to move with the arm engaging the arm above its pivot.
- 15 5. A sole sewing machine, having, in combination with the stitch forming devices, a 25

work support, an arm pivotally mounted below the work support and having its upper free end engaging the awl and needle slot of the work support, a welt channeling knife upon the upper end of the arm, a pivotally mounted brace engaging the arm above its pivot, and a bolt passing through and supporting the arm and brace. 30

In testimony whereof I, the said CARSON J. CADY, have signed my name to this specification in the presence of two subscribing witnesses. 35
